Patented May 25, 1920.

FIG. 1

FIG. 2

FIG. 3

INVENTOR

FREDERICK HACHMANN

By Edward E. Longan

ATTY.

UNITED STATES PATENT OFFICE.

FREDERICK HACHMANN, OF ST. LOUIS, MISSOURI, ASSIGNOR OF ONE-HALF TO DAVID M. HUTCHINSON, OF FERGUSON, MISSOURI, ONE-SIXTEENTH TO MONTE G. PRICE, OF EFFINGHAM, ILLINOIS, ONE-SIXTEENTH TO CHAUNCEY R. WATSON AND ONE-SIXTEENTH TO PHILIP E. MOODY, BOTH OF DETROIT, MICHIGAN.

SPARK-PLUG.

1,341,614.

Specification of Letters Patent. Patented May 25, 1920.

Application filed September 22, 1919. Serial No. 325,488.

To all whom it may concern:

Be it known that I, FREDERICK HACHMANN, a citizen of the United States, and resident of the city of St. Louis and State of Missouri, have invented certain new and useful Improvements in Spark-Plugs, of which the following is a specification, containing a full, clear, and exact description, references being had to accompanying drawings, forming a part thereof.

This invention relates to improvements in spark plugs and has for its primary object a spark plug provided with a channel shaped ring, the purpose of which is to remove accumulated carbon on the outside of the porcelain insulator and also on the inside of the casing.

A further object is to provide a spark plug with a cleaning member, so that the accumulation of carbon will be prevented on both the porcelain insulator and the casing.

In the drawings,

Figure 1 is an elevation of my invention with parts broken away and in section.

Fig. 2 an enlarged cross sectional view of the cleaning member made use of, and

Fig. 3 an enlarged view of the counter weight.

In the construction of my device, I make use of a casing 4 which is preferably of the ordinary construction. Within this casing is located the porcelain insulator 5 in which the electrode 6 is securely cemented and baked. The casing 4 is provided with a chamber 7, in which the vertical portion 8 of the porcelain insulator 5 is located.

In order to make a leak proof joint between the porcelain insulator 5 and the casing 6, I employ the gaskets 9 and the binding nut 10; these being of the ordinary construction are not described in detail.

The chamber 7 is provided with vertical walls 11, so that the walls 8 of the insulator will be spaced equally therefrom. In other words, the walls 8 and 11 will be parallel to each other.

The lower portion of the casing 4 is provided with an extension 12; this extension being recessed so as to form a seat for the ring 13. The inner surface 14 of this ring projects beyond the surface of the chamber 7, so as to form the shoulder 15. Surround-

ing the porcelain insulator 5, is placed the cleaning member 16; this member being ring shaped and channel shaped in cross section, (see Fig. 2), the walls 17 acting as scrapers against the wall 11 of the casing, and the wall 8 scraping the wall or vertical portion 8 of the insulator 5.

This cleaner is provided with a circumferential depression 19 into which the ring 20 fits. This ring may be split as shown in Fig. 3, or be made solid and acts as a counter weight to bring the cleaner 16 downward by gravity.

The cleaning member 16 is formed of aluminum as it has a higher specific heat than iron or brass, and will consequently burn up any carbon which may settle on it, and also will consume articles of carbon which may lodge in the casing or on the porcelain insulator in its passage upward and downward; this operation of the ring being controlled or caused by the explosion and exhaust in the engine cylinder or expansion chamber.

The operation of my device is as follows:

The plug having been secured in the explosion chamber of an internal combustion engine, and the engine started, the force of the explosion will cause the cleaning member to be driven upward in the chamber 7; the ring 20 acting as a counter weight together with the suction caused by the exhaust will draw the ring downwardly, its lowest limit being regulated by the ring 13, which ring will prevent the cleaning member 16 from dropping out of the chamber 7. In fact the ring 13 is not inserted in the spark plug until the cleaning member 16 and the counter weight 20 have been placed in position, so it will be readily seen that the device can be assembled as cheap as any plug of the present construction.

Another thing to be noted is that by the use of my plug there is virtually no change for the accumulation of carbon, which being a well known conductor of electricity is the cause of most spark plug trouble; this trouble being caused by carbon accumulating on the porcelain insulator, and the casing surrounding the insulator, and forming a solid bridge of carbon between the two electrodes, so that the electric current will flow through

without causing a spark to jump from one electrode to the other, and thus causing "missing" of the electrodes.

Having fully described my invention what 5 I claim is:

1. In a spark plug comprising a casing, a porcelain insulator secured within said casing, said insulator and casing having vertical parallel walls forming a chamber, 10 an aluminum cleaning ring provided with downwardly projecting flanges interposed between the insulator and the casing, said flanges acting as a scraper for the walls of the insulator and casing.
- 15 2. In a spark plug comprising a casing, a porcelain insulator secured within said casing, said insulator and casing having vertical parallel walls forming a chamber, an aluminum cleaning ring provided with downwardly projecting flanges interposed between the insulator and the casing, said flanges acting as a scraper for the walls of the insulator and casing, and a ring inserted 20 in the lower end of the casing for retaining the cleaning ring.
- 25 3. In a spark plug comprising a casing, a porcelain insulator secured within said casing, said insulator and casing having ver-

tical parallel walls forming a chamber, an aluminum cleaning ring provided with 30 downwardly projecting flanges interposed between the insulator and the casing, said flanges acting as a scraper for the walls of the insulator and casing, and a second ring located above the cleaning ring, said second 35 ring adapted to act as a counter weight.

4. In a spark plug comprising a casing, a porcelain insulator secured within said casing, said insulator and casing having vertical parallel walls forming a chamber, 40 an aluminum cleaning ring provided with downwardly projecting flanges interposed between the insulator and the casing, said flanges acting as a scraper for the walls of the insulator and casing, a ring inserted in 45 the lower end of the casing for retaining the cleaning ring, and a second ring located above the cleaning ring, said second ring adapted to act as a counter weight.

In testimony whereof I have signed my 50 name to this specification, in presence of two subscribing witnesses.

FREDERICK HACHMANN.
